UNITED STATES PATENT OFFICE

119,049

DESIGN FOR A TOY

Joseph Pavlicek, Montevideo, Minn.

Application October 21, 1939, Serial No. 87,790

Term of patent 3½ years

To all whom it may concern:

Be it known that I, Joseph Pavlicek, a citizen of the United States and resident of Montevideo, in the county of Chippewa, in the State of Minnesota, have invented a new, original, and ornamental Design for a Toy, of which the following is a specification, reference being had to the accompanying drawing, forming a part thereof.

I claim:

The ornamental design for a toy, as shown.

JOSEPH PAVLICEK.
